UNITED STATES PATENT OFFICE.

CLARENCE J. McCONNELL, OF DECATUR, ILLINOIS.

GAME APPARATUS.

SPECIFICATION forming part of Letters Patent No. 793,798, dated July 4, 1905.

Application filed January 19, 1905. Serial No. 241,894.

To all whom it may concern:

Be it known that I, CLARENCE J. McCONNELL, of the city of Decatur, county of Macon, and State of Illinois, have invented a certain Improved Game Apparatus, of which the following is a specification.

The object of this invention is to provide a game that will combine pleasant excitement with both mental and physical exercise.

10 The invention is embodied in a board provided with different sets or groups of pins, each set of which has a different scoring value, and a set of rings of various scoring values adapted to be pitched onto the pins of the board. The board is provided with a hinged cover, which stands against the wall of the room while the board is in use and protects the base-board from impact of mispitched rings. The board is square in horizontal outline. The general arrangement of the pins is in circular sets concentric with a central pin at different distances therefrom, and there are four pins, one in each corner of the board outside the outer circle of pins.

25 In the drawings forming part of this specification, Figure 1 is a perspective representation of the game-board, and Fig. 2 is a diagram of a set of rings.

The board A has a ledge B along its upper edge, and the cover C is hinged to a side of the board. A pin 20 projects upward from the center of the board. Three sets of pins 5, 10, and 15 encircle the central pin at different distances therefrom, and pins 25 are placed one in each corner of the board outside set 15. A complete set of rings comprises a plurality of single-value rings 1^v, and other rings having a double scoring value, 2^v, others having a triple scoring value, 3^v, and 40 still others having a quadruple scoring value, as 4^v. As a matter of preference there are seventeen single-value rings and one each of the other values; but this proportion may be varied. The rings of different values are distinguishable by external markings, preferably colors, and each ring of a certain value has the same color. For instance, the single-value rings may be red, the double-value

rings yellow, the triple-value rings blue, and the quadruple-value rings green.

50 The board is placed on the floor of a room with the cover against a wall, and a pitching-line is established some distance from the board, usually about eight feet. Each player is supplied with a set of rings, and each pitches 55 his or her rings onto the board, computes the score for the inning, and removes the rings before another player begins. As many may play as wish to, either as partners or as individuals, and a game usually comprises several 60 innings, preferably 10. Assuming that the scoring value of the different pins is: the central pin, twenty; pins of the inner circle, five each; pins of the intermediate circle, ten each; pins of the outer circle each fifteen, and corner-pins each 25, which are the proportionate values preferred, and the score of an inning will depend partly upon these values and partly upon the multiples of these values attributable to the different rings. If, for instance, a player pitches two red rings onto the central pin, a red ring onto a corner-pin, a green ring onto a pin of the inner circle, and a yellow ring onto a pin of the outer circle, the total score for that inning would be 75 one hundred and fifteen; but both multiplication and addition are involved in the mental calculation. The result should be reached at once, and as, under the rules of the game, each player must make his own calculations 80 the drill in mathematics tends to the development of accuracy and speed. The rings have to be picked up after being pitched. There are several in a set. Each player recovers his or her rings, and so the physical exercise 85 attending the pitching and the recovery of the rings is equal if not superior to a gymnastic drill or exercise.

Considerable skill may be developed in pitching the rings onto certain pins. As skill 90 develops interest increases, and so the incentive to the physical and mental exercise involved is continuously developing.

I claim—

1. A game apparatus, comprising a square 95 board having a central pin, sets of pins ar-

ranged in concentric circles at different distances from the central pin and pins in the corners of the board outside the outer circle of pins; and a set of rings of different colors 5 to indicate different scoring values.

2. A game apparatus, comprising a square board, a cover for the board hinged to one side thereof, a pin at the center of the upper surface of the board, sets of pins arranged in 10 concentric circles at different distances from

the central pin, pins in the corners of the board outside the outer circle of pins, and a set of rings of different colors to indicate different scoring values.

In testimony whereof I sign my name in the 15 presence of two subscribing witnesses.

CLARENCE J. McCONNELL.
